Primary Examiner — David Muller*(74) Attorney, Agent, or Firm* — Brinks Hofer Gilson & Lione(57) **CLAIM**

We claim the ornamental design for a vertebral augmentation needle, as shown and described.

DESCRIPTION

FIG. 1 is a top perspective view of a vertebral augmentation needle of the present invention;

FIG. 2 is a right side elevation view thereof, where a left side elevation view will substantially be a mirror image of the right side elevation view;

FIG. 3; is a distal end elevation view thereof;

FIG. 4 is a proximal end elevation view thereof;

FIG. 5 is a top plan view thereof; and,

FIG. 6 is a bottom plan view thereof.

The claimed ornamental design is shown in solid lines in the drawings. Any broken lines in the drawings form no part of the claimed design.
